UNITED STATES PATENT OFFICE.

LELAND S. ROSENER, OF SAN FRANCISCO, AND FRANK I. DOANE, OF BERKELEY, CALIFORNIA, ASSIGNEES TO THE PARAFFINE COMPANIES, INC., OF SAN FRANCISCO, CALIFORNIA, A CORPORATION OF DELAWARE.

PIPE-WRAPPING MACHINE.

Application filed June 27, 1922. Serial No. 571,198.

To all whom it may concern:

Be it known that we, LELAND S. ROSENER and FRANK I. DOANE, citizens of the United States of America, and residents, respectively, of the city and county of San Francisco, and Berkeley, county of Alameda, State of California, have invented a new and useful Pipe-Wrapping Machine, of which the following is a specification.

10 Our invention relates to pipe wrapping devices. One of the objects of the invention is the provision of an improved pipe wrapping machine in which the pipe is rotated and fed forwardly thru the machine 15 by the same feed rollers. Another object of the invention is the provision of a pipe wrapping machine in which the ratio between the speed of rotation and the speed 20 of longitudinal movement of the pipe may be readily adjusted to determine the pitch of the spiral characterizing the strip of covering as it is rolled upon the pipe.

Our invention possesses other objects and features of advantage, some of which, with 25 the foregoing, will be set forth in the following description of our invention. It is to be understood that we do not limit ourselves to the showing made by the said description, as we may adopt variant forms of the invention within the scope of the claims.

In the drawings, Fig. 1 is a front elevation of the machine, portions of the structure being broken away. Fig. 2 is a sectional view of a portion of the machine, the 35 plane of section being indicated by the line 2—2 of Fig. 1. Fig. 3 is a plan view of the machine.

In terms of broad inclusion, our invention comprises a machine in which a pipe may 40 be covered by a strip wound helically thereon. The end of the strip is applied at an angle to the pipe, and the pipe rotated and at the same time fed forwardly, so that the strip is drawn upon the pipe. The pipe 45 is rotated and fed thru the machine by a plurality of feed rollers, which are mounted for pivotal movement about an axis perpendicular to their axis of rotation, and means are provided for moving the rollers 50 on their respective pivotal axes so as to adjust the ratio between the speed of rotation and the speed of axial movement of the pipe. If the axis of rotation of the feed rollers is

parallel to the axis of the pipe, rotation of the feed rollers will effect merely a rotation 55 of the pipe, but if the rollers are turned out of such parallelism, each in equal degree, the pipe is not only rotated but fed forwardly as well, and the ratio between these two movements, that is to say, the pitch of the 60 spiral described by a given point on the surface of the pipe depends on the angularity of the adjustment. If the feed rollers are turned to an angle of 90° from the first position so that the rollers are turning in a 65 plane coincident with the axis of the pipe, no rotary movement is given to the pipe, but only axial movement.

Means are also provided for simultaneously driving the feed rollers; for permitting radial adjustment toward and from the axis of the pipe to accommodate different sizes of pipe; for simultaneously adjusting the angularity of the feed rollers to the axis 70 of the pipe; for feeding a strip of wrapping 75 material to the pipe; and for impregnating the wrapping material with a waterproof composition, such as asphalt, immediately before the wrapping material reaches the pipe.

More particularly, our machine comprises a frame of which the chief parts are a pedestal 2, and preferably three radial extensions 3, projecting from a central barrel 4. In each frame portion 3, a hollow shaft 6 is mounted for pivotal movement about the axis 7, which extends radially from the axis 8, passing thru the center of the barrel 4 and coincident with the axis of rotation 9 of the pipe 10.

Mounted for axial movement in the hollow shaft 6, but not rotatable therein because of the key 11, is a hollow shaft 12 provided with threads 13 and carrying a hand wheel 14 threaded thereon. A coil spring 16 is interposed between the hand wheel and a bridge plate 17. The hand wheel bears on one side against a portion of the frame, and by turning the hand wheel the sleeve 12 may be moved radially on its axis 7, the spring 16 tending to keep the adjustment fixed but permitting limited outward movement. The lower portion of the sleeve is provided with a yoke 18 within which a shaft 19 is journaled. A knurled feed roller 21 is fixed on the shaft so that the axis of

2
rotation 22 of the feed roller intersects the axis 7, which also passes midway between the lateral faces of the roller. On the end of the shaft 19 is a beveled gear 23 in mesh with a similar gear 24 fixed on a shaft 26, which is journaled in the sleeve 12 and extends upwardly therethru and thru the coil springs 16 and bridge plate 17, and thru a gear 27 splined on the end thereof. The gear 27 is provided with a hub 28 which is journaled in the upper end of the frame member 3. Rotation of the gear 27 thus effects the rotation of the feed roller 21 and a large gear 31 having its bearing on the end of the barrel 4, on which it is retained by the collar 32, provides means for simultaneously driving all three of the gears 27, so that the feed rollers 21 are all driven at the same speed. A spur gear 33 bolted to the side of the gear 31 meshes with the pinion of a power shaft 34 turned by any suitable prime mover.

Means are also provided for turning the shafts 6 simultaneously, to adjust the angularity of the feed rollers, that is to say, the angle which the axis 22 makes with the plane determined by the axis 7 and the axis 9. Fixed on each hollow shaft 6 is a segment of a gear 36 adapted to be meshed with a gear 37 mounted for rotation on the end of the barrel 4, opposite the mounting of the gear 31. The gear 37 is retained on the barrel by a collar 38 provided with brackets 39, in which the hand wheel controlled shaft 41 is journaled. The shaft 41 is provided with a worm 42 engaging worm teeth formed on the hub of the gear 37. Rotation of the shaft 41 by the hand wheel effects a turning of the gear 37 and a simultaneous movement of each of the hollow shafts 6 about their respective axes 7. Because of the irreversible character of the worm the shafts 6 are retained in their adjusted position without additional locking means.

45 From the above it will be clear that the feed rolls may be adjusted radially to engage a pipe of any desired size within the range of the machine and by then backing off the hand wheel a trifle, the rolls are 50 silently held against the pipe by the springs 16 which give sufficiently to permit the rolls to accommodate themselves to any inequalities in the surface of the pipe. The angularity of the feed rolls is then adjusted in 55 accordance with the width of the covering strip and the amount of the lap, if any, by the hand wheel 40. Rotation of the gear 31 effects a simultaneous rotation of the feed rollers and the rotation and axial progress 60 thru the machine of the pipe.

Means are also provided for feeding a strip of covering material impregnated with hot bituminous compound to the pipe. Arranged adjacent the mechanisms just described is the framework comprising a tank

51 in which a quantity of material such as asphalt may be heated by any suitable source of heat in the fire-box 52 formed in the lower portion of the frame. Elements 53 disposed on the frame are provided with means for mounting a roll 54 of the material to be wound on the pipe. This material 55 is led over a guide roller 57 downwardly into the body of hot asphalt over the roller 58 then upwardly past the scraping bars 59 which remove the surplus material clinging to the strip and over the guide roller 61, which is adjustable vertically on the slide-ways 62, by means of the screw 63. The strip then passes to the pipe at an angle determined by the pitch of the helix characterizing the wrapping as it is applied.

In Figs. 1 and 2 the feed rollers are shown at such a setting that only rotation of the pipe would be effected, but under service conditions it is obvious that the rotational axis of the roller 61 must be in parallelism with the rotational axis of the rollers 21, since the angularity of the feed roller axis 22 determines the pitch of the spiral winding, 90 and the roller 61 must of course be perpendicular to the direction in which the winding strip is delivered. The first length of pipe is fed thru the feed rollers and the winding strip started by hand. As the end 95 of the piece approaches the feed rollers, a suitable plug is inserted and another length of pipe attached. The operation of the machine is thus substantially continuous. The lengths of pipe are separated later as desired 100 by cutting thru the covering and removing the connecting plug.

The apparatus of our invention is particularly suitable for covering fabricated or cast pipes of varying diameters and may readily be adjusted to pipes of different sizes and to different conditions in the winding of the covering strip. A special factor of usefulness of our machine lies in the fact that it may be set up and operated at the 110 point where the pipe is to be used.

We claim:

1. In a machine for wrapping cylindrical objects, a feed roller, means for adjusting said feed roller about an axis perpendicular 115 to its axis of rotation, and means independent of said objects for rotating said feed roller.

2. In a machine for wrapping cylindrical objects, a yoke, a feed roller journaled in 120 said yoke, means for adjusting said yoke about an axis perpendicular to the rotational axis of said feed roller, and means independent of said objects for rotating said feed roller.

3. In a machine for wrapping cylindrical objects, a yoke, a feed roller journaled in 125 said yoke, means for adjustably turning said yoke about an axis perpendicular to the rotational axis of said feed roller and for fix-

ing said yoke in the adjusted position, and means independent of said objects for rotating said feed roller.

4. In a machine for wrapping cylindrical objects, a feed roller, means for adjusting said feed roller about an axis perpendicular to its axis of rotation, means independent of said objects for rotating said feed roller, and means for adjusting the position of said feed roller in said perpendicular axis.

5. In a machine for wrapping cylindrical objects, a feed roller, means for adjusting said feed roller about an axis perpendicular to its axis of rotation, means independent of said objects for rotating said feed roller, means for adjusting the position of said feed roller in said perpendicular axis, and means for resiliently holding said feed roller in the adjusted position.

20 6. In a machine for wrapping cylindrical objects, a yoke, a feed roller journaled in said yoke, means for rotating said feed roller to propel said objects therepast, means for turning said yoke about an axis perpendicular to the rotational axis of said feed roller, and means for axially adjusting the position of said yoke.

30 7. In a machine for wrapping cylindrical objects, a frame, a hollow shaft journaled in said frame, means for turning said shaft on its journal axis, a sleeve axially slidably mounted in said shaft for rotary movement therewith, means for moving said sleeve longitudinally in said shaft, a feed roller mounted on said sleeve, and means for rotating said feed roller.

40 8. In a machine for wrapping cylindrical objects, a frame, a hollow shaft journaled in said frame, means for turning said shaft on its journal axis, a sleeve axially slidably mounted in said shaft for rotary movement therewith, means for moving said sleeve longitudinally in said shaft, a feed roller mounted on said sleeve, a driving shaft arranged in said sleeve, means for rotating said driving shaft, and driving mechanism connecting said driving shaft and feed roller.

50 9. In a machine for wrapping cylindrical objects, a frame, a hollow shaft journaled in said frame, means for turning said shaft on its journal axis, a sleeve, a sleeve axially slidably mounted in said shaft for rotary movement therewith, means for moving said sleeve longitudinally in said shaft, a feed roller mounted on said sleeve, a gear journaled on said frame, a driving shaft in said sleeve slidably mounted in said gear for rotation therewith, driving mechanism connecting said driving shaft and feed roller and means for driving said gear.

55 10. In a machine for wrapping cylindrical objects, a frame, a hollow shaft journaled in said frame, means for turning said shaft on its journal axis, a sleeve axially slidably

mounted in said shaft for rotary movement therewith, means for moving said sleeve longitudinally in said shaft, a feed roller mounted on said sleeve, means for rotating said feed roller, means for axially adjusting said sleeve in said shaft, and a spring interposed between said sleeve and frame.

60 11. In a machine for wrapping cylindrical objects, a frame, a hollow shaft journaled in said frame, a gear segment on said shaft, a gear in mesh with said segment, a worm for turning said gear, a feed roller mounted on said shaft for rotary movement therewith and axial movement in respect thereof, and means for driving said feed roll.

70 12. In a machine for wrapping cylindrical objects, a yoke, a feed roller journaled in said yoke, means independent of said objects for rotating said feed roller, means for turning said yoke about an axis perpendicular to the rotational axis of said feed roller, and resilient means for holding said yoke against axial movement.

80 13. In a machine for wrapping cylindrical objects a frame, a plurality of feed rollers circumferentially spaced in said frame, means for simultaneously rotating said feed rollers, and means for simultaneously adjusting the axis of rotation of each of said feed rollers to any position from coincidence with a plane passing thru the longitudinal axis of said object to perpendicularity with said plane.

90 14. In a machine for wrapping cylindrical objects, a frame, a plurality of feed rollers circumferentially spaced in said frame, means for simultaneously rotating said feed rollers, means for simultaneously adjusting the axis of rotation of each of said feed rollers to any position from coincidence with a plane passing thru the longitudinal axis of said object to perpendicularity with said plane, and means for adjusting the position of said feed rollers radially from the axis of said object.

100 15. In a machine for wrapping cylindrical objects, a frame, a plurality of feed rollers circumferentially spaced in said frame, means for simultaneously rotating said feed rollers, means for simultaneously adjusting the axis of rotation of each of said feed rollers to any position from coincidence with a plane passing thru the longitudinal axis of said object to perpendicularity with said plane, means for adjusting the position of said feed rollers radially from the axis of said object, and resilient means tending to prevent outward radial movement of said feed rollers.

110 16. In a machine for wrapping cylindrical objects, a frame, a plurality of hollow shafts journaled radially in said frame about the longitudinal axes of the object to be wrapped, means for simultaneously turning said shafts on their respective journal axes,

- a sleeve axially slidably mounted in each shaft for rotary movement therewith, means for moving each sleeve longitudinally in its shaft, a feed roller mounted on each sleeve, 5 a driving shaft arranged in each sleeve, means for simultaneously rotating said driving shafts, and driving mechanism connecting each driving shaft and its associated feed roller.
- 10 17. In a machine for wrapping cylindrical objects, a frame, a plurality of hollow shafts journaled radially in said frame about the longitudinal axes of the object to be wrapped, a gear segment on each of said 15 shafts, a gear in mesh with said segments, means for turning said gear to adjust said shafts simultaneously about their respective journal axes and for fixing the shafts in the adjusted positions, a sleeve axially slidably mounted in each shaft for rotary movement therewith, means for longitudinally adjusting each sleeve in its shaft, a feed roller mounted on each sleeve, a driving shaft arranged in each sleeve, a gear in which each 20 shaft is slidably mounted for rotation therewith, a driving gear in mesh with the last named gears and driving mechanism connecting each driving shaft and its associated feed roller.
- 25 18. A machine for wrapping cylindrical objects, comprising a feed roller for engaging said object, means for rotating said feed roller to propel said objects therewith, means for adjusting said feed roller about an axis perpendicular to its axis of rotation to vary the ratio between the speed of rotation and the axial movement of the object, and means for feeding a strip of wrapping material to said object.
- 30 19. A machine for wrapping cylindrical objects, comprising a feed roller for engaging said object, means for rotating said feed roller, means for adjusting said feed roller about an axis perpendicular to its axis 35 of rotation to vary the ratio between the speed of rotation and the axial movement of the object, a body of fluid, and means for feeding a strip of wrapping material thru said fluid to said object.
- 40 20. In a machine for wrapping cylindrical objects, a frame, a plurality of feed rollers circumferentially spaced in said frame, means for simultaneously rotating said feed rollers, means for simultaneously adjusting the axis of rotation of each of said feed rollers to any 45 position from coincidence with a plane passing thru the longitudinal axis of said object to perpendicularity with said plane, a body of fluid, and means for feeding a strip of wrapping material thru said fluid to the object being wrapped.
- 50 21. A machine for wrapping pipe, comprising a frame, a plurality of sleeves journaled radially in said frame about the longitudinal axis of the pipe, means for simultaneously turning said sleeves on their respective journal axes, a feed roller to engage said pipe mounted on each sleeve, a drive shaft arranged in each sleeve and operatively connected to the associated feed 55 roller, means for simultaneously rotating said driving shafts to effect the rotation of said feed rollers and the resultant rotation of said pipe, and means for feeding a strip of wrapping material to said pipe.
- 60 22. A machine for wrapping pipe with an impregnated covering, comprising a frame, a plurality of sleeves journaled radially in said frame about the longitudinal axis of the pipe, means for simultaneously turning 65 said sleeves on their journal axes, a feed roller to engage said pipe mounted on each sleeve, a drive shaft arranged in each sleeve, and operatively connected to the associated feed roller, means for simultaneously rotating 70 said driving shafts to effect the rotation of said feed rollers and the resultant rotation of said pipe, a body of impregnating material, and rollers over which a strip of covering material is led thru said impregnating 75 material to said pipe.
- 75 In testimony whereof, we have hereunto set our hands the said LELAND S. ROSENER at San Francisco, California, this 13th day of June, 1922, and the said FRANK I. DOANE, 80 at Los Angeles, California, this 15th day of June, 1922.
